(57) **CLAIM**

The ornamental design for a produce storage container, as shown and described.

DESCRIPTION

FIG. 1 is a top, front and right side perspective view of the first embodiment of a produce storage container showing our new design;

FIG. 2 is a bottom, front and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top, front and right side perspective view of the second embodiment of a produce storage container showing our new design;

FIG. 10 is a bottom, front and left side perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.
